UNITED STATES PATENT OFFICE

136,816

DESIGN FOR A GENERATIVE CUTTING MACHINE

Edward W. Miller, Springfield, Vt., assignor to
The Fellows Gear Shaper Company, Springfield, Vt., a corporation of Vermont

Application September 9, 1942, Serial No. 108,156

Term of patent 14 years

To all whom it may concern:

Be it known that I, Edward W. Miller, a citizen of the United States, residing at Springfield, in the county of Windsor, State of Vermont, have invented a new, original, and ornamental Design for a Generative Cutting Machine, of which the following is a specification, reference being had to the accompanying drawings, forming a part thereof.

In the drawings—

Fig. 1 is a front perspective view of a generative cutting machine showing my new design;

Fig. 2 is a rear perspective view of said machine;

Fig. 3 is a plan view of the machine; and
Fig. 4 is an end perspective view as seen from the left of Fig. 1, omitting the housings and guards shown in broken lines in the other three views.

The dominant features of the design reside in the portions shown in full lines.

I claim:

The ornamental design for a generative cutting machine, substantially as shown and described.

EDWARD W. MILLER.
